DESIGN FOR A CARPET SWEEPER

Findley Williams, Park Ridge, Ill., assignor
to Bissell Carpet Sweeper Company, Grand Rapids, Mich.

Application January 13, 1937, Serial No. 67,039

Term of patent 14 years

To all whom it may concern:

Be it known that I, Findley Williams, a citizen of the United States, residing at Park Ridge, in the county of Cook and State of Illinois, have invented a new, original, and ornamental Design for a Carpet Sweeper, of which the following is a specification, reference being had to the accompanying drawing, forming part thereof, in which:

Fig. 1 is a perspective view of a carpet sweeper,
showing my new design.

Fig. 2 is an end elevational view of the carpet
sweeper.

Fig. 3 is a front elevational view taken from the right of Fig. 2.

I claim:

The ornamental design for a carpet sweeper,
as shown.

FINDLEY WILLIAMS.
